UNITED STATES PATENT OFFICE.

HIROTSUNE TESSHU NAKAMIZO, OF LOS ANGELES, CALIFORNIA.

DISAPPEARING BOW-REST AND SHACKLE.

1,300,187.

Specification of Letters Patent.

Patented Apr. 8, 1919.

Application filed September 18, 1917. Serial No. 192,013.

To all whom it may concern:

Be it known that I, HIROTSUNE TESSHU NAKAMIZO, a subject of the Emperor of Japan, residing at Los Angeles, in the 5 county of Los Angeles and State of California, have invented new and useful Improvements in Disappearing Bow-Rests and Shackles, of which the following is a specification.

10 This invention relates to a bow rest and shackle for automobile tops and the like.

One of the objects of the present invention is to provide a combination bow rest and clamping shackle of the disappearing 15 type for automobile tops and the like, which is adapted to be telescoped into the body of the machine when not required, for instance when the top is raised, thus leaving the sides or body of the car clear and free 20 of projecting clamps, brackets, and like obstructions, which are not only a source of nuisance but also serve to detract from the general appearance of the car. Another object of the invention is to provide a holder 25 for the reception of the shackles, which may be placed between the walls of the body, and in conjunction therewith to provide a novel mechanism for projecting the shackles when required. Further objects will herein- 30 after appear.

The invention consists of the parts and the construction and combination of parts as hereinafter more fully described and claimed, having reference to the accompanying 35 drawings, in which—

Figure 1 is a side elevation of the rear end of a car, showing the application of the invention.

Fig. 2 is an end view of said car, showing 40 the top raised.

Fig. 3 is a perspective view of the rear portion of said car.

Fig. 4 is a plan view of the holder, partly in section, showing one shackle in its telescoped position and the opposite shackle in 45 a projected position.

Fig. 5 is a cross section on line 5—5 of Fig. 4.

Fig. 6 is a side elevation of Fig. 4.

50 Fig. 7 is a cross section on line 7—7 of Fig. 6.

Fig. 8 is a modification of the structure shown in Figs. 4 and 6.

Referring to the drawings in detail, A 55 indicates the body of an automobile, 2 the top and 3 the bows and stretchers by which

the top is supported. Extending crosswise of the car, between the rear walls of the body, is a tube or holder 4, and slidably mounted in each end of said holder is a 60 plunger 5, to the outer end of which is pivotally attached, as at 6, a shackle 7.

Interposed between the plungers is a coil spring 8 and limiting the outward movement of each plunger is a pin or stop 9 65 which projects into a slot 10 formed in the upper side of the holder 4. Pivotaly mounted, as at 11, exteriorly of the holder is a pair of latch arms 12. The inner ends of these arms are slotted, as at 13, and connected through a link 14 with a lever 15 pivotally mounted, as at 16, in a bracket secured within the body of the car.

Mounted adjacent to the upper end of the lever 15 is a push button 17. This button 75 projects through the rear side of the car and, when depressed, engages the upper end of the lever 15, thereby rocking the same, together with the latches 12, about their pivots to a position where the pins 9 are disengaged. The tension of the coil spring 8 will then force the plungers outwardly to the projected position shown at one end of Figs. 4 and 6. The latches 12, together with 80 the lever 15, return to normal locking position the moment the push button is released as each latch is provided with a spring 18 for this purpose.

Formed on the outer end of each plunger is a shoulder 5^a. This shoulder may be lined 90 with felt or like material and serves as a rest for the bows or stretchers, generally indicated at 3. The plungers, when projected, therefore, primarily serve as a rest for said bows and stretchers when the top is folded, 95 as shown in Fig. 1, and at the same time serve as a support for the clamping shackle, generally indicated at 7. The shackle employed may be of suitable construction and is adapted to embrace the bows, as shown 100 at 20, being secured in said position by means of a thumb screw 21 or the like carried by one of the bows.

Pivotaly attached to the main link 7^a of each shackle is a head or button member 105 22. This button serves as a closure for each end of the holder 4 when the plungers and shackles are telescoped therein, thus providing a neat finish and a flush appearance when they are not employed, the plungers 110 being projected when required by merely depressing the button 17 and they may be tele-

scoped when not employed by merely folding the upper links of the shackle into the position shown at 7^b, (see Fig. 6) and pushing the plunger and shackle inwardly 5 against the tension of the spring 8; the pin 9 being engaged by the latch the moment the shackle has been completely telescoped. They are thus automatically locked in this 10 position and cannot be projected until released by the latches when the push button is depressed.

The device as a whole is simple and substantial in construction and may be readily applied to any make of car as the space required by the tube or holder 4 is such that it can always be placed between the walls forming the rear part of the body. All projecting clamps, brackets, or like devices can thus be eliminated and the general appearance 20 of the car is consequently improved thereby.

Another form of the device is shown in Fig. 8. The push button, together with the coil spring 8, is here eliminated and a separate tube or holder 4^a is employed for each plunger. The structure of the plunger and the shackle will remain identical with the exception that the button 22 is provided with a pull extension 23 to permit the plunger and shackle to be pulled out when required. It is otherwise held in position by the button 22 when it is telescoped by providing a tapering fit which will frictionally secure it.

35 The materials and finish of the several parts comprising the device may be such as the experience and judgment of the manufacturer may dictate.

Having thus described my invention, what 40 I claim and desire to secure by Letters Patent is—

1. A disappearing bow rest and shackle for automobile tops comprising a holder secured within the body of the car, and a combination bow rest and shackle adapted to be telescoped in or extended with relation to the holder to project exterior of the body.

2. A disappearing bow rest and shackle for automobile tops comprising a holder secured in the body of the car, a bow rest slidably mounted in the holder, and a clamping shackle pivotally attached to the bow rest, said shackle and bow rest being adapted to be telescoped or projected with relation to the holder.

3. A disappearing bow rest and shackle for automobile tops comprising a holder secured in the body of the car, a bow rest slidably mounted in the holder, a clamping shackle pivotally attached to the bow rest, said shackle and bow rest being adapted to be telescoped or projected with relation to the holder, and means for limiting the sliding movement of the bow rest whether it is 65 projected or telescoped.

4. The combination with the bows of a foldable vehicle top and the body of the vehicle, of a tubular holder secured in the body crosswise thereof, and having its outer ends flush with the body, and a pair of combination bow rests and clamping shackles adapted to be telescoped within the holder or projected from each end of the holder to extend exterior of the body.

5. The combination with the bows of a 75 foldable vehicle top and the body of the vehicle, of a tube extending crosswise of the body between the walls thereof, a combination bow rest and clamping shackle adapted to be received in each end of the 80 tube and to telescope therein, means for securing said members within the tube when telescoped, and means for automatically projecting the same when required.

6. The combination with the bows of a 85 foldable vehicle top and the body of the vehicle, of a tube extending crosswise of the body between the walls thereof, a plunger slidably mounted in each end of the tube, a clamping shackle pivotally attached to the 90 outer end of each plunger, each plunger and attached shackle being adapted to telescope within the tube, and means for securing each plunger and shackle against projection when telescoped.

7. The combination with the bows of a 95 foldable vehicle top and the body of the vehicle, of a tube extending crosswise of the body between the walls thereof, a plunger slidably mounted in each end of the tube, a clamping shackle pivotally attached to the 100 outer end of each plunger, each plunger and attached shackle being adapted to telescope within the tube, means for securing each plunger and shackle against projection 105 when telescoped, a spring within the tube interposed between the plungers, said spring adapted to automatically project the plungers, means for releasing the plungers to permit the spring to project the same, and means for limiting the outward movement 110 when they are projected.

8. The combination with the bows of a 115 foldable vehicle top and the body of the vehicle, of a tube extending crosswise of the body between the walls thereof, a plunger slidably mounted in each end of the tube, a clamping shackle pivotally attached to the 120 outer end of each plunger, each plunger and attached shackle being adapted to telescope within the tube, a spring within the tube interposed between the plungers to project the same, a slot formed in each end of the tubes, a stop pin secured on each plunger projecting through said slots, a pair of latches secured on the tube adapted to engage the pins to secure the plungers and attached shackles from being projected when they are telescoped within the tube, and means for rocking the latches to disengage 125 130

them from the pins to permit the spring to project the plungers.

9. The combination with the bows of a foldable vehicle top and the body of the vehicle, of a tube extending crosswise of the body between the walls thereof, a plunger slidably mounted in each end of the tube, a clamping shackle pivotally attached to the outer end of each plunger, each plunger and attached shackle being adapted to telescope within the tube, a spring within the tube interposed between the plungers to project the same, a slot formed in each end of the tube, a stop pin secured on each plunger projecting through said slots, a pair of latches secured on the tube adapted to engage the pins to secure the plungers and attached shackles from being projected when they are telescoped within the tube, means for rocking the latches to disengage them from the pins to permit the spring to project the plungers, said means comprising a push button, a pivotally mounted lever adapted to be rocked when engaged by the button, and a link connecting said lever with the latches.

10. The combination with the bows of a foldable vehicle top and the body of the vehicle, of a tube secured in the body and ex-

tending crosswise of the same, the ends of 30 said tube being flush with the exterior sides of the body, and a support for the bows slidably mounted in each end of the tube, and adapted to be projected to support the bows when the top is folded, and to be telescoped within the tube when the top is raised. 35

11. The combination with the bows of a foldable vehicle top and the body of the vehicle, of a tube secured in the body and extending crosswise of the same, the ends of 40 said tube being flush with the exterior sides of the body, a support for the bows slidably mounted in each end of the tube, and adapted to be projected to support the bows when the top is folded, and to be telescoped within the tube when the top is raised, and a clamping shackle on each supporting member adapted to secure the bows to the supporting members when the top is folded, said clamping 45 shackles being also adapted to be telescoped within the tube in unison with the supporting members, and also adapted to be projected with relation to the ends of the tube when the supporting members are projected. 50 55

In testimony whereof I have hereunto set my hand.

HIROTSUNE TESSHU NAKAMIZO.
